UNITED STATES PATENT OFFICE.

NAPOLEON B. DOUGLASS, OF BERKELEY, CALIFORNIA.

WALL-BED.

1,053,481.

Specification of Letters Patent. Patented Feb. 18, 1913.

Application filed March 28, 1912. Serial No. 686,846.

To all whom it may concern:

Be it known that I, NAPOLEON B. DOUGLASS, citizen of the United States, residing at Berkeley, in the county of Alameda and State of California, have invented new and useful Improvements in Wall Beds, of which the following is a specification.

This invention relates to wall beds and pertains especially to a reversible wall bed mounted on a panel in an opening in the wall and adapted to be turned through an arc of 180°, so that the bed may be exposed into the room, and ready for use, or turned into the closet and concealed when not in use.

A particular object of the present invention is to provide a practical wall bed of this character which is a simple and economical structure, and so constructed and arranged that a full-sized, double bed may be made to turn in and out of a closet, having an opening of less width than the bed; the closet having an ordinary door of the usual dimensions, for closing it when not in use; the bed being mounted entirely independent of the door and in no wise having its movements affected or controlled by the door itself.

The invention consists of the parts and the combination and construction of parts is hereinafter described and claimed, having reference to the accompanying drawings, in which—

Figure 1 is a perspective of the invention. Fig. 2 is a rear elevation of the bed mounting. Fig. 3 is a horizontal section through the closet and bed, showing the bed disclosed in the closet. Fig. 4 is a detail of the foot of the bed mounting at right angles to the position shown in Fig. 2. Fig. 5 is similar to Fig. 4, indicating the position of the parts when the bed is opened out for use. Figs. 6, 7, 8 and 9 are diagrammatic representations in plan, showing the successive positions of the bed as it is turned from the closet into the room through a complete arc of 180°.

A represents a closet or recess designed to house a folding bed 2, and having an ordinary door 3 behind which the bed is concealed when not in the room. The bed 2 is a full-sized double bed and the door 3 is an ordinary door of considerably lesser width than the bed.

The bed 2 is mounted on a specially designed bracket 4, Fig. 2, which latter is fixed

on a vertical shaft 5; this shaft 5 being loosely journaled in upper and lower bracket arms 6, the outer ends of the arms 6, having suitable pintles which are stepped at 7 respectively, into appropriate sockets in the top and bottom of the recess opening, but a little rearward of the plane of the door 3 and a little to one side of the vertical center of the opening.

8 is an automatic reversing link which has one end pivoted inside the closet at 9; the other end pivoted to the bottom edge of the panel to one side of the vertical carrying shaft 5, as shown at 10. The position of the pivot 9 with respect to the pivot 7 of the bed-carrying brackets is of prime importance in this invention, in order to give the proper curvature to the path of the bed when swung in and out of the closet, so as to clear the wall 17 of the door frame. I have found that both pivots 9 and 7 are placed comparatively close together on the same side of the vertical center of the bed when the same is in the closet in the position as shown in Fig. 6.

The bed 2 is hung from the arms 4 by the links 11—12 Figs. 4 and 5, or by any other appropriate means, so that the bed can be raised into vertical position parallel with shaft 5 when not in use, or extended into horizontal position so as to be used as a bed.

Any suitable means may be employed to hold the bed upright, as by the counter-weight 15. The chief novelty however, in the present invention is in the discovery of the means for mounting this bed in a closet having a door or opening less than the width of the bed, and to be able to move this bed in and out of this closet through this narrow opening; thereby doing away with the wide opening, and the wide panel. This is accomplished by the particular arrangement of the pivots 7 and 9, both considerably to one side and to the same side of the vertical shaft pivot 5, when the bed is in either of its fully reversed positions, Figs. 6 and 9.

13 is a comparatively narrow panel mounted over a portion only of the width of the bed and sufficient only to form a finish with the door opening when the bed is brought into the room, into the position shown in Fig. 9; this panel 13 having a projecting edge portion 14 adapted to form a joint with the adjacent door jamb 15.

In operation, assuming the parts to be in

the position shown in Figs. 3 and 6 with the bed upright within the closet and the closet door closed, to open the bed out for use the door 3 is first swung back on its pivots or 5 hinges 16 into the position shown in Fig. 7, the bed then is revolved on its pivots 7 outwardly in the direction of the arrow Fig. 7; the bed turning successively through the positions shown in Figs. 7 and 8 until 10 it assumes the position shown in Fig. 9. This reversal is automatically effected by the combined action of the supporting bracket and link 8.

Inasmuch as it is desirable to use a door 15 opening of minimum width, one of the prime characteristics of the present invention has been the positioning of this bed arrangement with respect to the door opening, so that a double width bed mounted 20 independently of a door of considerably narrower width, is permitted to swing in and out of this opening without interference, and reverse itself through an arc of 180°. This is done by placing the pivot 7 sufficiently rearward of the normal plane of the door 3 so that when the bed is in the closet the door 3 can be closed, and placing the pivot 9 of the link 10 almost directly back of the lower pivot 7, so that this pivot 9 25 is considerably to one side of the center of the bed when the same is in the position indicated in either Figs. 6 or 9, and always on the same side of the center of the pivot 5; both the pivots 7 and 9 being approximately central of the door way.

When the parts are fully reversed, as shown in Fig. 9, the lower bracket 6 and link 8 stand in cross position, as shown, because the pivot 10 has changed its position 40 from one side of the center 5 to the other. In all these different positions however, both these pivots 7 and 9 are always on the same side of the plane of the panel 13, carried by the bed.

45 By mounting the bed in the manner shown, it allows ready access to the closet. If it is desired to facilitate the turning of

the bed when the door 3 is opened, there may be placed a suitable latch 18 on the door 3 and when the bed is in the closet and the door 3 is closed, will be adapted to engage some portion as 19, on the bed-carrying structure. When the door 3 is thus opened, it will carry the bed-carrying structure and bed with it a short distance until it is turned 55 out far enough into the room to be grasped by the attendant and the reversal completed: the latch 18 slipping off the pin 19, due to the different paths of travel of the bed and the door 3.

Having thus described my invention, what I claim and desire to secure by Letters Patent is—

The combination with a receptacle having an opening, of a bed mounted on a bed-carrying structure and independent of the door, said bed wider than the opening, an arm at the top and another arm at the bottom supporting the bed and said arms pivoted at their inner ends at the top and bottom of the opening so that the bed-carrying structure may turn on vertical pivots and in and out of said opening, connections between the arms whereby they are made to work in unison so as to maintain the axis 65 of oscillation of the bed always in a true vertical, a reversing link pivoted at one end to the bed-carrying structure, and having the other end pivoted within the closet, and rearward of the pivot of the lower arm, 70 said pivot for the link and the lower arm pivot being on the same side of the center of the bed when the bed is in either of its completely reversed positions, and both the 75 said pivots being approximately midway between the sides of the door opening.

In testimony whereof I have hereunto set my hand in the presence of two subscribing witnesses.

NAPOLEON B. DOUGLASS.
